3, 1939, Serial No. 297,761

8 Claims. (Cl. 66—190)

This invention relates to knit fabrics having elastic threads incorporated therein and more particularly to knit fabrics of the type described suitable for use as hosiery tops and it is an object of this invention to provide a rib fabric for use as a hosiery top which has a continuous elastic thread incorporated therein intermittently, preferably in portions only of successive courses.

10 In the drawing, the figure is a substantially diagrammatic view showing the relations of the fabric loops and the incorporated elastic yarn in a fabric in accordance with this invention, the view showing the loops of portions of two 15 rib tops knit continuously.

In the drawing the fabric portion is shown as it comes from the machine, the courses at the bottom of the sheet being the first knit. The figure is broken as all courses shown are not consecutive and portions of some of the wales are, in the drawing, offset from the positions in which they actually occur in the fabric. The courses shown, beginning at the bottom, are the courses shortly before the press-off of one rib 25 top and the courses then continue through the press-off of that rib top, the start-up of the succeeding rib top and into the body portion. The rib top shown is a rib top such as is made by the usual hosiery top "ribber" and is shown for the 30 purpose of illustration only, as it is to be understood the invention is equally applicable to rib fabric knit on other types of rib knitting machines.

The rib tops illustrated are shown as knit in a continuous string of a single continuous main or body yarn A, the needles being operated to form the make-up or starting course 1 of a top in the revolution in which the cylinder needles are operated to cast off their loops in the press-off course at the completion of a knit top. As shown, the dial needles retain their loops during the press-off so successive rib tops are joined together by the loops of the wales knit by the dial needles. Following the start-up course 1 45 there is knit a course 2 of rib fabric and a course 3 knit on the cylinder needles only, the dial needles taking yarn but not casting off the previously drawn loops. Following course 3 are two courses 4 and 5 knit on the cylinder needles only, the dial needles being inactive but retaining the loops previously taken. During the knitting of courses 4 and 5 the elastic thread R is laid in back of the cylinder needles and below the dial needles so as to be held between the cylinder 50 and dial needle wales of the fabric for approxi-

mately 1½ to 1¾ courses and then withdrawn, the holder for the elastic thread being rotated where the needle cylinder is stationary so as to lay in the elastic thread continuously in advance of the knitting point. Two courses 6 and 7 of rib fabric are then knit, the elastic thread being laid in between cylinder and dial needle wales for a part of each course and being then withdrawn for the remainder of that course or revolution of the knitting cams, the elastic yarn 10 holder remaining stationary each time at the needle at which the elastic thread is withdrawn until the elastic thread guide is again operated to position the elastic thread for laying-in in the next or a succeeding course or revolution 15 when the elastic thread holder is again advanced.

Following course 1, a course 8 is then knit on the cylinder needles only, the dial needles taking yarn but retaining the loops previously taken. The elastic thread guide is operated to lay in 20 the elastic thread for a portion of a revolution during the knitting of course 8 and also during the knitting of the following courses 9 and 10 knit on the cylinder needles only, the dial needles being inactive but retaining the loops previously 25 taken. Courses 11, 12, 13 etc., of rib fabric are then knit, the number of courses being sufficient to provide a rib top of the desired length and the elastic thread is incorporated in the fabric 30 for the desired portion of each of the desired courses.

In the drawing the elastic thread is shown as incorporated for a portion of each of a number of the rib fabric courses of a top, as from course 11 to course 30, but it is to be understood the 35 elastic thread need not be incorporated in all courses but may be incorporated in recurring courses of any desired spacing. It is also to be understood that the number of needle wales for which the elastic thread is incorporated in each 40 course, as shown in the figure, is purely an arbitrary selection and that the extent for which the elastic thread is incorporated in a course may be varied; thus as shown in courses 40 to 45 42 and 56 to 58 the elastic thread is incorporated for but one-half the extent to which it is incorporated in courses 11 to 24. Changing the extent to which the elastic thread is incorporated in a course varies the amount of elastic 50 thread in the fabric and the tension exerted thereby when stretched. Thus, in courses 11 to 24 the elastic thread may be incorporated for a fourth or a fifth of each course and the elastic thread at any one needle wale is in every 55 fourth or fifth course, while in courses 40 to 58

where it is incorporated for an eighth or a tenth of a course the elastic thread, at any one wale, is in every eighth or tenth course and the elastic thread incorporated in that portion of a top is 5 but a half of what is incorporated in the courses 11 to 24.

When the elastic thread has been incorporated for a sufficient number of courses it is withdrawn, as in course 30, and kept from the 10 needles until it is again presented to the needles at the beginning of the next top knit, the elastic thread being allowed to float from where it was withdrawn in the knitting of one top to 15 where it is inserted in the knitting of the succeeding top.

In the top illustrated several courses of rib fabric, as courses 81 to 83, are knit after the withdrawal of the elastic thread, then there are knit a loose course 84, several rib fabric courses, as 20 85 to 88, a course 89 in which the cylinder needles knit and the dial needles take yarn and retain the loops previously drawn, two courses 90 and 91 in which the cylinder needles knit and the dial needles are inactive but retain the loops previously 25 taken and rib fabric courses 92 and 93. The cylinder needles are then operated to press off the loops of course 93 and during the same revolution of the cam ring both the cylinder and dial needles are operated to take yarn and the 30 dial needles to cast off the loops of course 93, thus placing on all the needles the loops for the starting course 1.

This application is a division of my co-pending application Serial No. 194,505, filed March 35 7, 1938.

I claim:

1. Seamless tubular knit fabric comprising a plurality of courses and a continuous elastic thread incorporated unknit for a portion only of 40 each of a plurality of courses, said portions extending progressively around the entire fabric.

2. Seamless tubular knit fabric comprising a plurality of courses and a continuous elastic thread incorporated unknit in said fabric in staggered portions only of a plurality of courses, said staggered portions being offset progressively around the fabric.

3. Circular knit rib fabric comprising a plurality of successive courses of loops of a yarn and a continuous elastic thread incorporated unknit for portions only of successive courses, said portions extending progressively around said fabric.

4. Circular knit rib fabric comprising a plurality of courses and a continuous elastic thread incorporated unknit for a portion only of each of a plurality of courses, said elastic thread being incorporated to a different extent in different courses and said portions being offset progressively around said fabric.

5. Circular knit fabric comprising a plurality of courses and a continuous elastic thread incorporated unknit in staggered portions only of a plurality of courses, said portions being progressively offset around said fabric.

6. Circular knit fabric comprising a plurality of courses and a continuous elastic thread incorporated unknit in portions only of each of a plurality of courses, said portions extending progressively around said fabric.

7. Circular knit fabric comprising a plurality of courses and a continuous elastic thread incorporated unknit in portions only of each of a plurality of courses, said portions extending progressively around the fabric.

8. Circular knit fabric comprising a plurality of courses and a continuous elastic thread incorporated unknit in portions only of each of a plurality of courses, successive incorporated portions of said elastic thread engaging offset groups of needle wales entirely around said fabric.

JAMES L. GETAZ.
